(57) **CLAIM**

The ornamental design for a scooter, as shown and described.

DESCRIPTION

FIG. 1 is a top, front, right side perspective view of a scooter, showing my new design;

FIG. 2 is a bottom, rear, left side perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged view of a portion labelled 9 in FIG. 1;

FIG. 10 is an enlarged view of a portion labelled 10 in FIG. 1; and,

FIG. 11 is an enlarged view of a portion labelled 11 in FIG. 2.

The broken lines in the drawings depict portions of the scooter that form no part of the claimed design.

The dash dot dash lines in FIG. 1, FIG. 2, FIG. 9, FIG. 10 and FIG. 11 are for the purpose of depicting the cut line of the enlarged view and form no part of the claim.

1 Claim, 11 Drawing Sheets
